Primary Examiner — Lilyana Bekic(74) *Attorney, Agent, or Firm* — Wick Phillips Gould & Martin, LLP(57) **CLAIM**

The ornamental design for a powered air purifying respirator blower, as shown and described.

DESCRIPTION

FIG. 1 is a top perspective view of a powered air purifying respirator blower in accordance with the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines shown in the drawings depict portions of the powered air purifying respirator blower that form no part of the claimed design.
